UNITED STATES PATENT OFFICE.

GEORGE R. MOORE, OF LYONS, IOWA.

IMPROVEMENT IN COAL-STOVES.

Specification forming part of Letters Patent No. 63,926, dated April 16, 1867.

To all whom it may concern:

Be it known that I, GEORGE RODNEY MOORE, of Lyons, in the county of Clinton and State of Iowa, have invented certain new and useful Improvements in Coal-Burning Stoves; and I do hereby declare that the following is a full and exact description thereof, reference being had to the accompanying drawings, and the letters of reference marked thereon.

My invention relates to a means of smothering the fire, so as to check the combustion of the fuel without extinguishing the fire during the night, or at any time when the heat of combustion is not required, and of obviating the necessity of rekindling.

In the accompanying drawings, Figure 1 is a perspective view of a cylindrical sheet-iron stove containing my improvements, and Fig. 2 is a vertical section through the same from front to rear.

A is the cylindrical outer casing; B, the fire-pot or interior fire-brick lining. C is a cover, located at the top of the fire-pot or fire-brick lining, (turning on a hinge, c,) which may be closed down over the top of the fire-pot to check the combustion of the fuel when retiring at night, or when for any reason active combustion is not desired. When this cover C is turned up into a vertical position, as shown in red, Fig. 2, it forms a partition dividing the combustion-chamber from the exit-flue, and creates a diving-flue back of the combustion-chamber, through which the products of combustion must descend to reach the smoke-pipe

D. It is obvious that the cover C may be set at any desired angle to regulate the draft of the stove when in ordinary use. The draft will be increased by turning the cover forward at an angle of from twenty to forty-five degrees.

When it is desired to check the combustion of the fuel for any considerable time, as upon retiring at night, a sufficient quantity of fresh coal should be placed in the fire-pot and the door C closed down over it. In this condition the fire may be preserved for many hours, or even for days, with scarcely any consumption of the fuel, and when the cover C is raised active combustion will be immediately resumed.

This improvement is designed mainly for stoves in which soft coal is used. Should it be used in connection with hard coal, some apertures in the cover C, or other openings, for the escape of gas, will be required.

What I claim as my invention, and desire to secure by Letters Patent, is—

The hinged cover C, so arranged and operating as to smother the fire and check combustion when turned down to a horizontal position, and to form a diving-flue between the combustion-chamber and the smoke-pipe when turned to a vertical position, substantially as described.

GEO. R. MOORE.
